UNITED STATES PATENT OFFICE.

CLARENCE W. BLACKBURN, OF SOUTH GREENSBURG, PENNSYLVANIA.

TOY.

1,385,517.

Specification of Letters Patent. Patented July 26, 1921.

Application filed December 16, 1920. Serial No. 431,237.

To all whom it may concern:

Be it known that I, CLARENCE W. BLACKBURN, a citizen of the United States, residing at South Greensburg, in the county of 5 Westmoreland and State of Pennsylvania, have invented certain new and useful Improvements in Toys; and I do declare the following to be a full, clear, and exact description of the invention, such as will enable others skilled in the art to which it 10 pertains to make and use the same.

This invention relates to an improved toy and one object of the invention is to provide a toy of the track and marble type in 15 which the marbles or rollers will be mounted in a receptacle above the upper end portion of the track and a guard provided to feed the marbles out of the receptacle one at a time, the actuating means for the guard being connected with a section of the track whereby marbles passing over the track will cause the guard to be moved and release the 20 marbles from the receptacle.

Another object of the invention is to so 25 construct the guard for the receptacle outlet that it will permit the marbles to readily pass out of the receptacle but at the same time very efficiently prevent more than one marble from passing out with each operation of the guard.

Another object of the invention is to so 30 construct the toy that the sections which form the track may be positioned one above the other with each track section positioned 35 at an incline and having its lower end portion above the upper end of a lower track section, the lower end portions of the sections being pivotally mounted so that they may swing down into engagement with track 40 sections beneath them.

Another object of the invention is to so 45 construct this toy that a signal bell may be mounted adjacent the lower end of the lowermost track section and the bell sounded in timed relation to the passage of the marbles over the pivoted portions of the track sections.

Another object of the invention is to so 50 construct this toy that there will be no danger of the marbles bouncing from the track bars.

Another object of the invention is to so 55 construct this toy that it will be comparatively simple in construction and strong and durable and very efficient in its operation.

This invention is illustrated in the accompanying drawing, wherein:

Figure 1 is a view showing the improved 60 toy principally in side elevation and partially in section.

Fig. 2 is a horizontal sectional view taken along the line 2—2 of Fig. 1.

Fig. 3 is a vertical sectional view taken along the line 3—3 of Fig. 1.

Fig. 4 is a fragmentary sectional view 65 taken through a portion of the receptacle and track structure.

Fig. 5 is a sectional view taken along the line 5—5 of Fig. 1.

Fig. 6 is an enlarged perspective view of 70 the guard controlling passage of the marbles through the outlet of the receptacle.

This toy is provided with a base having a center bar 1, side strips 2 and end blocks 3 which connect the center bar with the side 75 strip 2. A tray 4 is mounted between the center bar 1 and one of the side strips 2 in which the marbles may be placed when the toy is not in use and one portion of the center bar is cut away to provide an inclined 80 seat 5 for directing the marbles into the space 6 when the toy is in use. Standards 7 are carried by the end blocks and bracing strips 8 are secured to the center bar 1 upon opposite sides thereof as shown in Figs. 1 and 2 and 85

also in Fig. 3 so that the track bars 9 may be firmly supported. These track bars are positioned one above the other as clearly shown in Fig. 1 and extend downwardly with the adjacent track bars extending in 90 opposite directions and the lower free end portions 10, of the upper track bars pivotally mounted so that the free end portions of the upper bars may swing downwardly to engage the upper end portions of the track bars 95

beneath them. The track bars will each be formed from side strips as shown in Fig. 3 which are spaced apart, the side strips of the major portion of the track bar being held in spaced relation by spacing strips 100

9' and the side strips which form the pivoted end portions 10 being held in spaced relation by a spacing strip 10' which in addition to providing spacing means extends between the side strips of the major portion 105 of the track bar and receives a pivot pin 11. Side arms 12 are connected with the pivoted end portions of the track bars, the arms 12 with the exception of those carried by the pivoted end portion of the second track 110

C. W. BLACKBURN.

UNITED STATES PATENT OFFICE.

CLARENCE W. BLACKBURN, OF SOUTH GREENSBURG, PENNSYLVANIA.

TOY.

1,385,517.

Specification of Letters Patent. Patented July 26, 1921.

Application filed December 16, 1920. Serial No. 431,237.

To all whom it may concern:

Be it known that I, CLARENCE W. BLACKBURN, a citizen of the United States, residing at South Greensburg, in the county of

5 Westmoreland and State of Pennsylvania, have invented certain new and useful Improvements in Toys; and I do declare the following to be a full, clear, and exact description of the invention, such as will enable others skilled in the art to which it appertains to make and use the same.

This invention relates to an improved toy and one object of the invention is to provide a toy of the track and marble type in 15 which the marbles or rollers will be mounted in a receptacle above the upper end portion of the track and a guard provided to feed the marbles out of the receptacle one at a time, the actuating means for the guard being connected with a section of the track whereby marbles passing over the track will cause the guard to be moved and release the marbles from the receptacle.

Another object of the invention is to so 25 construct the guard for the receptacle outlet that it will permit the marbles to readily pass out of the receptacle but at the same time very efficiently prevent more than one marble from passing out with each operation.

Another object of the invention is to so 30 construct the toy that the sections which form the track may be positioned one above the other with each track section positioned 35 at an incline and having its lower end portion above the upper end of a lower track section, the lower end portions of the sections being pivotally mounted so that they may swing down into engagement with track

40 sections beneath them.

Another object of the invention is to so construct this toy that a signal bell may be mounted adjacent the lower end of the lowermost track section and the bell sounded in 45 timed relation to the passage of the marbles over the pivoted portions of the track sections.

Another object of the invention is to so 50 construct this toy that there will be no danger of the marbles bouncing from the track bars.

Another object of the invention is to so 55 construct this toy that it will be comparatively simple in construction and strong and durable and very efficient in its operation.

This invention is illustrated in the accompanying drawing, wherein:

Figure 1 is a view showing the improved toy principally in side elevation and partially in section.

Fig. 2 is a horizontal sectional view taken along the line 2—2 of Fig. 1.

Fig. 3 is a vertical sectional view taken along the line 3—3 of Fig. 1.

Fig. 4 is a fragmentary sectional view 65 taken through a portion of the receptacle and track structure.

Fig. 5 is a sectional view taken along the line 5—5 of Fig. 1.

Fig. 6 is an enlarged perspective view of 70 the guard controlling passage of the marbles through the outlet of the receptacle.

This toy is provided with a base having a center bar 1, side strips 2 and end blocks 3 which connect the center bar with the side 75 strip 2. A tray 4 is mounted between the center bar 1 and one of the side strips 2 in which the marbles may be placed when the toy is not in use and one portion of the center bar is cut away to provide an inclined 80 seat 5 for directing the marbles into the space 6 when the toy is in use. Standards 7 are carried by the end blocks and bracing strips 8 are secured to the center bar 1 upon opposite sides thereof as shown in Figs. 1 and 2 and 85 also in Fig. 3 so that the track bars 9 may be firmly supported. These track bars are positioned one above the other as clearly shown in Fig. 1 and extend downwardly with the adjacent track bars extending in 90 opposite directions and the lower free end portions 10, of the upper track bars pivotally mounted so that the free end portions of the upper bars may swing downwardly to engage the upper end portions of the track bars 95 beneath them. The track bars will each be formed from side strips as shown in Fig. 3 which are spaced apart, the side strips of the major portion of the track bar being held in spaced relation by spacing strips 100 9' and the side strips which form the pivoted end portions 10 being held in spaced relation by a spacing strip 10' which in addition to providing spacing means extends between the side strips of the major portion 105 of the track bar and receives a pivot pin 11. Side arms 12 are connected with the pivoted end portions of the track bars, the arms 12 with the exception of those carried by the pivoted end portion of the second track 110

section being weighted as shown at 13 to normally retain the pivoted end portions in a raised position and out of engagement with the following track bars. Guard strips 14 are positioned about the upper end portions of the lower track bars and a signal bell 15 is suspended from between the side strips of the lower track bar for engagement by a striker 16 which is pivotally mounted between the hanger brackets 17 and extends upwardly for engagement by a marble moving along the lower track bar section.

When operating this device, the marbles 18 will be placed in the receptacle 19 which receptacle is carried by the side strips 8 and is positioned at an incline with its lower end portion provided with an outlet 20 through which the marbles will pass and drop upon the upper track bar 9, a guide strip 21 being provided to direct the marbles downwardly and side plates 22 similar to the plates 14 being provided to prevent the marbles from moving transversely off of the upper track when first landing thereon. It is desired to have the marbles or rollers 18 fed one at a time through the outlet opening 20 and in order to do so, there has been provided a guard which feeds the marbles through the opening one at a time. This guard is provided with a rocker shaft 23 which is journaled in the side walls of the receptacle 19 and is provided with fingers 24 which extends longitudinally of the receptacle and are curved downwardly as shown in Figs. 4 and 6. One end portion of the rocker shaft extends through the side wall of the receptacle and is flattened as shown at 25 thus providing a flat head with which the upper end of a lever strip 26 is rigidly connected. This lever strip extends downwardly from the rocker shaft and is then bent to extend longitudinally of the upper track bar and has its free end portion twisted and extending downwardly at an incline. The free end of the lever is connected with the arm 12 of the pivoted end portion of the second track bar by means of a link 27 so that when a marble passes over this pivoted end portion of the second track bar, the guard will receive movement. An arm 28 extends from the lever beneath the receptacle and is provided with upwardly curved fingers 29 which extend through slots 30 in the bottom of the receptacle adjacent the outlet opening 20. These fingers 29 curve toward the free ends of the fingers 24 but terminate in spaced relation to the fingers 24 and are of such length that when the lever 26 is swung downwardly and brings the free end portions of the fingers 24 close to the opening 20, the fingers 29 will not extend above the bottom of the receptacle 19 thereby permitting the marbles to move downwardly until stopped by one of the

marbles engaging the free end of the fingers 24.

The trough will hold a predetermined number of marbles or rollers and when playing the game a sufficient number of marbles will be used to fill the receptacle and leave one additional marble. In the present illustration, thirteen marbles are required to fill the receptacle and the fourteenth will be placed upon the upper track bar beneath the receptacle. This marble will pass down the upper track bar and will tilt the pivoted end portion thereof so that the pivoted end portion rests upon the second track bar and thus permits the marble to pass easily onto the second track bar. After passing from the pivoted end of the upper track bar, this pivoted end is swung up to a raised position and the marble will then pass down the second track bar and over the pivoted end thereof onto the third track bar. In passing over the pivoted end portion of the second track, the lever 26 will be swung upwardly so that the fingers 29 move upwardly behind the marble engaged by the fingers 24 and in front of the following marble. This marble which will then be in front of the fingers 29 will be released from the fingers 24 as the fingers 24 move upwardly to the position shown in Fig. 4 and the marble will drop through the opening 20 down upon the upper track bar. The marbles will thus be successively permitted to pass through the opening 20 and when the toy is in operation, the marbles on the different track bars will reach the lower ends thereof at approximately the same time. As each marble passes along the lowermost track bar, it will strike the handle of the striker 16 and this will cause the bell to be sounded, thus sounding a bell each time the marbles reach the lower ends of the track bars. The marbles will drop upon the inclined chute 5 and will fall into the pocket 6 from which they may be removed and placed in the tray 4.

There has thus been provided a toy which will operate very efficiently in the manner described, the marbles being released at the proper time and the signal bell being sounded when the marbles reach the lower ends of the track bars.

What is claimed is:

1. A toy comprising a series of oppositely disposed inclined tracks positioned one above the other and each having a pivotally mounted lower end portion movable into and out of engagement with the upper end of a succeeding track bar, arms extending from the pivoted end portions of the tracks, certain of said arms being weighted and the arm of one pivoted end portion unweighted, a receptacle above the upper track having an outlet above the upper track, rollers in said receptacle freely movable for passing suc-

cessively through the outlet onto the upper track, and a guard for the outlet operatively connected with the unweighted arm and moved by a roller passing over its coöperating pivoted track end to permit a single roller to pass out of the receptacle and retain other rollers in the receptacle.

2. A toy comprising a pair of oppositely disposed inclined tracks positioned one above the other, the lower track having a pivotally mounted lower end portion, arms extending from the pivoted track end, a receptacle above the upper track having an outlet, and a guard for delivering rollers one at a time through the outlet operatively connected with the arms of the pivoted track end and receiving movement when a roller passes over the track and swings the same downwardly, said guard comprising a rocker shaft journaled transversely in the receptacle and having fingers extending longitudinally of the receptacle above the outlet, a lever connected with the rocker shaft, an arm extending from said lever beneath the receptacle and having fingers extending upwardly through slots in the receptacle and terminating in spaced relation to the fingers of said rocker shaft, and a link connecting the lever with the arm of its coöperating pivoted track end.

3. A toy of the character described including a roller receptacle having an outlet, a rocker shaft journaled transversely in the receptacle and having a finger extending longitudinally of the receptacle above the outlet, a lever connected with the rocker shaft, an arm extending from said lever beneath the receptacle and a finger extending upwardly through a slot in the receptacle and terminating in spaced relation to the finger of said rocker shaft, and actuating means connected with said lever for imparting movement to the same.

4. A toy comprising a frame, track bars carried by the frame one above the other and downwardly inclined, each having a free lower end portion terminating short of and in spaced relation to the upper end of the succeeding track bar and having a section of its free end pivotally mounted for vertical swinging movement into and out of engagement with the upper end of the track bar beneath it, and means counter-balancing the pivoted end of each track bar to normally retain the same in a raised position whereby a pivoted track end may swing down to deposit a roller upon a lower track bar and then return to a raised position to allow the roller to pass beneath the pivoted track end.

5. A toy of the character described including a roller receptacle having side walls and a bottom provided with an outlet and a guard for the outlet comprising a rocker shaft journaled in the side walls, fingers extending from the rocker shaft longitudinally of the receptacle above the outlet and arched upwardly and having their ends normally positioned for extending in front of a roller in the receptacle to hold the roller against passing through the outlet, a lever connected with one end of said rocker shaft, an arm extending from the lever beneath the receptacle and having fingers curved upwardly and extending through slots in the bottom of the receptacle for engaging a roller to the rear of the roller engaged by the fingers of the rocker shaft and holding the second roller against movement when the lever is moved to rotate the rocker shaft and swing fingers of the rocker shaft upwardly to permit the first roller to pass through the outlet opening.

In testimony whereof I have hereunto set my hand.

CLARENCE W. BLACKBURN.
